UNITED STATES PATENT OFFICE.

JAMES F. TIGHE, OF PHILADELPHIA, PENNSYLVANIA.

DRAINBOARD FOR SINKS.

1,149,478.

Specification of Letters Patent. Patented Aug. 10, 1915.

Application filed March 19, 1915. Serial No. 15,654.

To all whom it may concern:

Be it known that I, JAMES F. TIGHE, a citizen of the United States, residing at Philadelphia, county of Philadelphia, and State of Pennsylvania, have invented a new and useful Improvement in Drainboards for Sinks, of which the following is a full, clear, and exact description, reference being had to the accompanying drawings, which form a part of this specification.

The object of my invention is to provide a drain-board for kitchen sinks so constructed that the drain-board when in use is supported independently of, and preferably spaced from, the sink, and which is capable when not in use, of being moved away from the sink and there maintained in its normal horizontal position and also of being folded down toward or against the wall.

20 A preferred embodiment of the invention is shown in the accompanying drawings, in which—

Figure 1 is a plan view of the sink and drain board, the latter in operative relation to the sink. Fig. 2 is a front elevation of same, partly in section. Fig. 3 is an end view of same, partly in section. Fig. 4 is a similar view with the drain board swung into the position it may occupy when not in use. Fig. 5 is a plan view, with the drain board in the same position as in Fig. 4.

The sink *a* is of ordinary construction, having an upright splash-plate or wall-protector *b* at the rear, and is rigidly supported by brackets *c*.

The drain-board *e*, *per se*, is of the usual construction, but is supported and made movable by the following construction. Secured at the rear edge of the bottom of the drain board are hinges *f*, which are slidable and turnable upon pivot rods *g* extending between ears *h* attached to the front lower edge of a ledge *d* secured to the wall.

Attached to the wall below ledge *d* is an ear *i* between which and the ledge *d* is turnably supported a bracket *k* having a horizontally extending arm adapted to swing forward into the position shown in Figs. 1, 2 and 3 to support the drain-board, or rearward into the position shown in Figs. 4 and 5 to allow the drain-board to swing down into a vertical position.

m and *n* are abutments or pins adapted to cooperate with the bracket *k* as hereinafter described. It will be noted that the pins are spaced apart, measuring along the length

of the drain-board, and that pin *m* is located a greater distance back of the front edge of the drain-board than is pin *n*.

Assuming that the drain-board is in operative position relative to the sink, it will be noted that the discharge end of the drain-board overlies one edge of the sink and is spaced therefrom in a vertical direction. The bracket *k* has been swung out and extends at right angles to the wall, abutting against the pin *m* and supporting the drain-board horizontally. From this position the drain board may be moved to the right, as shown in broken lines, Fig. 1, the pin *m* sliding the bracket *k* into the broken-line position shown. The bracket *k* is still in position to support the drain-board, which therefore remains in horizontal position, although spaced from and out of operative relation with the sink.

By again noting the full-line operative position of the drain board shown in Fig. 1, it will be observed that even if the supporting bracket *k* is swung independently toward the rear, it will abut against the pin *n* and cannot, therefore, be moved out of supporting position, so that it is impossible for the drain-board to fold down against the sink. When, however, the drain board has been moved to completely clear the sink, as in the broken-line position, Fig. 1, the pin *n* has moved, with the drain-board, so far to the right that when the bracket *k* is swung toward the rear it will clear the pin *n*. When the bracket is swung entirely to the rear so that it underlies the ledge *d*, as shown in Fig. 4, the drain-board may be folded or dropped down into a vertical position as shown in that figure.

When it is desired to restore the drain-board to operative position, it is swung up on its pivot rods, the bracket is then swung out against pin *m*, and then the drain-board is pushed to the left into the full-line position shown in Fig. 1; the bracket, also, if desired, being moved against the pin *m* so that it assumes a position at right angles to the supporting plate *c*.

By the foregoing construction, there is no joint between the sink and drain-board in which dirt can collect and all parts of the sink and drain-board may be maintained clean and sanitary. It will be noted that the downwardly-extending lip at the discharge end of the drain-board is convexly curved, so that water will drop off the end

of same and cannot run back along the bottom of the drain-board. The drain-board, when not in use, occupies virtually no space and is entirely out of the way. The construction is such that it may be readily and inexpensively adapted to existing constructions whereby the drain-board is in rigid relation to the sink.

Having now fully described my invention, 10 what I claim and desire to protect by Letters Patent is:

1. The combination with a drain-board movable to and from a horizontal position and also slidable when in a horizontal position, of means, movable into and out of operative position, adapted to support the drain-board in horizontal position but locked by the drain-board from moving out of operative position when the drain-board is 20 slid to one of its horizontal positions.

2. The combination with a drain-board movable to and from a horizontal position and also slidable when in a horizontal position, of means supporting the drain-board 25 in either horizontal position but adapted to be moved out of supporting position when the drain-board is moved toward one position, and an abutment on the drain-board locking the supporting means from moving 30 out of operative position when the drain-board is in its other position.

3. The combination with a drain-board arranged to swing from a vertical position 35 to a horizontal position and also movable longitudinally, of a pivoted bracket arranged to swing away from the drain-board to clear the same and allow it to swing down into a vertical position and also to swing under the drain-board to support it in horizontal position when either in or out of its normally operative longitudinal position and an abutment on the drain board adapted 40 to lock the bracket from swinging away from supporting position when the drain-board is in said position but adapted, when the drain board is moved away from said position, to move into position to allow the bracket to swing away from supporting position.

4. The combination with a drain-board 45 arranged to swing from a vertical position

to a horizontal position and also movable longitudinally of a pivoted bracket arranged to swing away from the drain-board to clear the same and allow it to swing down into a 55 vertical position and also to swing under the drain-board to support it in horizontal position when either in or out of its normally operative longitudinal position, an abutment on the drain-board limiting the movement 60 of the bracket when swung into supporting position and a second abutment on the drain board adapted to lock the bracket from swinging away from supporting position 65 when the drain-board is in its normally operative longitudinal position but adapted, when the drain-board is moved away from said position, to allow the bracket to swing away from supporting position.

5. The combination with a horizontal ledge, of a pivot rod along the ledge, a drain board swingable on said rod and also slid- 70 able thereon, a bracket pivoted on a vertical axis and having an arm adapted to swing out under the drain board to support it in 75 a horizontal position and in under the ledge to allow the drain board to swing down on its pivot, and an abutment on the drain-board adapted to lock the bracket from swinging out of supporting position except 80 when the drain-board is moved away from its normally operative position.

6. The combination with a horizontal ledge, of a pivot rod along the ledge, a drain board swingable on said rod and also slid- 85 able thereon, a bracket pivoted on a vertical axis and having an arm adapted to swing out under the drain board to support it in a horizontal position and in under the ledge 90 to allow the drain board to swing down on its pivot, and two abutments on the drain-board, one nearer than the other to one end and to the rear edge of the drain board, adapted to coöperate with the bracket substantially as described.

In testimony of which invention, I have hereunto set my hand, at Philadelphia, on this 18th day of March, 1915.

JAMES F. TIGHE.
